UNITED STATES PATENT OFFICE.

GEORGE WRIGHT, OF VON ORMY, TEXAS.

CHAIR AND COUNTER.

1,359,118.

Specification of Letters Patent. Patented Nov. 16, 1920.

Application filed May 22, 1920. Serial No. 383,532.

To all whom it may concern:

Be it known that I, GEORGE WRIGHT, a citizen of the United States, residing at Von Ormy, in the county of Bexar and State of Texas, have invented new and useful Improvements in Chairs and Counters, of which the following is a specification.

This invention relates to chairs, and has particular reference to means for mounting a chair with relation to a counter, table or the like, so that the chair can be slid to a position beneath the counter when not in use and readily moved to a position for use when desired, by one positioned behind the counter.

Another object of the invention resides in the provision of a chair of particular construction, and wherein both the seat and back of the chair are relatively movable, so as to occupy positions for use as the chair is moved from beneath the counter, and to occupy a folded position when the chair is moved beneath the counter.

In carrying out my invention, I provide the front wall of the counter with a door disposed adjacent each chair, a door opening inwardly of the counter, and simultaneously with the movement of the chair to a position for use.

Other objects and advantages will appear as the following detail description is read in connection with the accompanying drawing, the invention residing in the construction, combination and arrangement of parts as claimed.

In the drawings forming part of this application like numerals of reference indicate similar parts in the several views and wherein:

Figure 1 is a front elevation of a counter showing the position of the chairs with respect to the counter.

Fig. 2 is a vertical sectional view through the counter showing one of the chairs in side elevation and in position beneath the counter.

Fig. 3 is a similar view showing the chair in extended position for use.

Fig. 4 is a view showing the rear elevation of a chair folded, the counter being partly in section.

Fig. 5 is an enlarged fragmentary view showing the connection between the chair

and door which is opened when the chair is extended for use.

Fig. 6 is a view of one of the hinge members forming part of the front of the chair.

Fig. 7 is a view of the hinge member forming part of the back of the chair.

Referring to the drawings in detail, 10 indicates a counter of any wellknown construction, the front wall 11 of which includes a plurality of inwardly opening doors 12, one of these doors being disposed adjacent each of the chairs B'. 55

Each chair includes a seat portion 14 supported by the front and rear members C and D respectively, corner blocks 14' being arranged between the rear member D and the seat 14. The rear member D projects a slight distance above the seat 14 as shown. Each of the members C and D includes a fixed section 15 and a movable section 16, the latter sections being hinged at 17 to swing in the same direction, so as to assume 75 a horizontal position when the chair is projected from beneath the counter as shown in Fig. 3, or to assume a vertical position when the chair is positioned beneath the counter as shown in Fig. 2. Secured to the 80 movable section 16 of the member C adjacent each side thereof, is a pair of U-shaped elements 18 and through each pair is slidably fitted a rod 19 having a broad extremity or end portion 20 to prevent the rod 85 from being separated from the elements 18. Also secured upon the movable section 16 of the member D, are sleeves 21 through each of which slides the hinged member 22, the latter being hinged as at 22' to the member D, while the forward end of the member 22 is connected with a link 23. This link is 90 vertically disposed and pivotally associated with a transversely disposed member 24 hinged as at 25 to the lower end of the chair back 26, the forward end of the member 24 being pivotally mounted upon the front member C of the chair structure. It will be noted that both of the movable sections 95 16 of the respective members C and D are hingedly mounted upon the base or foundation of the counter A, and are only connected with the members C and D through the instrumentality of the rods 19 and the hinged members 22. The back of the chair 100 26 includes spaced parallel members as

shown in Fig. 4, these members sliding through slots in the seat 14 of the chair, it being understood that the chair back 26 is raised when the chair is moved from beneath the counter for use and lowered when the chair is arranged beneath the counter in its folded position. For moving the chair B, I make use of two flexible elements indicated at 30 and 31, the former being trained over a small pulley 32 mounted upon the rear wall of the counter, and thence under a pulley 33 arranged at the base of the counter, the terminal of the flexible element 30 being secured to the member of the chair as at 34. The opposite end of this flexible element projects through an opening in the counter and is arranged within convenient reach of the attendant. The other element 31 is trained over a pulley 32 similar to the pulley 32 above mentioned, but this element is directly connected with the member C of the chair, as at 35. Manifestly, when a pull is exerted upon the element 30, by the attendant standing behind the counter, the flexible element 30 operates to project the chair B from beneath the counter A. When a pull is exerted upon the flexible element 31 it moves the chair from its projected position to its folded position beneath the counter.

In practice, assuming that the chair is in its folded position, and arranged beneath the counter as shown in Fig. 2, and that it is desired to move the chair to a position for use, the flexible element 30 is pulled upon as above stated, and the chair B is obviously projected from beneath the counter, during which time, the movable element sections 16 of the front and rear members C and D of the chair move upon their pivots 17 from a vertical to a horizontal position as shown in Fig. 3. However, when the chair is projected from beneath the counter through the instrumentality of the flexible element 30, it does not assume its full and extended position, as it is susceptible of sliding movement with respect to the horizontally disposed sections 16, and for this purpose I provide the member D of the chair with a handle 36 which is adapted to be grasped by the user of the chair for moving the latter outwardly from the counter A. When the chair is moved in this manner, the rod 19 and the hinged member 22 slide outwardly upon the sections 16. The broad extremity 20 of the rod 19 limits the movement of the rod in this direction while the joint between the hinged members 22 and the links 23 co-operating with the sleeves 21 limit the movement of the members 22 in an outward direction. As shown in Fig. 2 the links 23 which are connected with the hinged members 22 and the transverse member 24 are inclined forwardly, it being further noted that the back 26 of the chair is

not lowered to lie wholly at one side of the member D, and that the seat 14 of the chair is in an elevated position, but when the chair is projected from beneath the counter and subsequently moved away from the counter in a manner above described, the relative change in position of parts causes the back 26 of the chair to assume a position for use as shown in Fig. 3, the seat 14 being lowered a distance equal to the height of the movable section 16 of the member D. When it is desired to move the chair from its extended to its folded position beneath the counter, a pull is exerted upon the flexible element 31 which moves the chair in a direction of the counter, causing the sections 16 to turn upon their pivots 17 returning the sections to their normal vertical positions. During the return of these sections to their normal positions the back 26 is lowered and the seat 14 elevated so that as the chair moves beneath the counter the parts are returned to the position as shown in Fig. 2. The pulley 37 is suspended from the underside of the top of the counter and arranged over this pulley is a cable 38 one end of which is secured to the movable section 16 of the member D chair construction, while the opposite end of the cable supports the weight 39. This acts as a counter balance to facilitate the returning of the chair and its associated parts to their normal position.

When the chair B is projected from beneath the counter for use, it is not spaced far enough from the front wall of the counter for the comfort of the user, so that in order to provide ample space for the legs and feet of the user, I provide in the front wall of the casing a plurality of inwardly swinging doors 40, one of these doors being arranged adjacent each chair B. Each door is connected to the adjacent chair by means of an arm 41 which has one end pivotally connected to a slotted link 42, the latter in turn being secured to a right angularly disposed slotted plate 43 mounted upon the base of the counter as shown in both Figs. 2 and 5. The plate 43 is connected to the movable section 16 of the member C of the chair by means of a link 44 so that when this section 16 assumes a horizontal position, incident to the movement of the chair to its extended position the arm 41 is moved in a direction to open the door 40. The door opening together with the opening in the counter for this chair, provides ample space for the legs or feet of the user of the chair. It is of course apparent that the door is automatically closed when the chair is moved to a position beneath the counter.

While it is believed that from the foregoing description the nature and advantages of the invention will be readily apparent, I desire to have it understood that I do not limit myself to the details herein shown

and described, and that such changes may be resorted to when desired as fall within the scope of what is claimed.

What I claim is:—

- 5 1. The combination with a counter, of a chair capable of movement to a position beneath the counter, or to a position beyond the counter for use, an inwardly opening door forming a part of the front wall of the counter, and a connection between the chair and said door whereby the latter is automatically opened and closed by movement of the chair to a projected position for use or to a position beneath the counter.
- 10 2. The combination with a counter, of a chair mounted upon the counter to be positioned beneath the latter or projected beyond the counter for use, means for controlling the movements of the chair and operable from a position behind the counter, an inwardly swinging door forming part of the front wall of the counter and arranged immediately adjacent said chair, and a connection between the chair and door, whereby the latter is automatically opened when
- 15 20 25

the chair is moved to a projected position, and automatically closed when the chair is moved to a position beneath the counter.

3. The combination with a counter, of a chair mounted thereon for movement to a position beneath the counter, or for movement to a position beyond the counter, said chair including a seat and a back movable to assume position for use when the chair is projected or a folded position when the chair is moved beneath the counter.

4. The combination with a counter, having an opening in the front thereof, of a chair mounted to be projected through said opening to a position beneath the counter or to a position beyond the counter for use, said chair including a seat and spaced parallel members supporting the seat, one of said members closing the opening in the counter when the chair is positioned beneath the counter, and means operable from a position back of the counter for controlling the movements of said chair.

In testimony whereof I affix my signature.
GEORGE WRIGHT.
